UNITED STATES PATENT OFFICE.

HERMAN A. WEIDENBACH, OF BUFFALO, NEW YORK.

MULTIPLE CENTRIFUGAL GOVERNOR.

1,072,888.

Specification of Letters Patent. Patented Sept. 9, 1913.

Application filed May 24, 1911. Serial No. 629,248.

To all whom it may concern:

Be it known that I, HERMAN A. WEIDENBACH, a citizen of the United States of America, residing at Buffalo, in the county 5 of Erie and State of New York, have invented certain new and useful Improvements in Multiple Centrifugal Governors, of which the following is a full, clear, and exact description.

10 One of the objects of my invention has been to provide a governor which shall be entirely inclosed within a casing.

Another object has been to provide a governor in which the amount of movement of 15 the reciprocating parts shall be multiplied, thus making a very compact device.

Furthermore, my device is very sensitive to the slightest change of the speed of revolution thereof and may be easily and quickly 20 adjusted to govern at any desired speed.

My governor has few working parts and will not easily get out of order.

I have accomplished these and other advantages, which will be apparent to those 25 skilled in the art, by my device hereinafter described.

Reference is to be had to accompanying drawings, which form part of this specification.

30 In the drawings like characters of reference indicate like parts in the several views of which:

Figure 1 is a vertical sectional elevation of my governor and is taken on the center 35 line thereof. Fig. 2 is a transverse sectional view of the same and is taken on line A—B of Fig. 1. Fig. 3 is a vertical sectional elevation of a modification of my governor and is taken on the center line thereof. Fig. 4 40 is a sectional view of a fragmental portion of my governor showing the use of gear segments having a different pitch radius than those shown in Figs. 1 to 3.

Referring now to the drawings and more 45 particularly to Figs. 1 and 2, 5 is the central shaft of my governor which is designed to be revolved by the engine which it is to govern. The said shaft is provided with lugs 6 near its upper end in which are secured two screw-threaded pivot pins 7 and 8. These pivot pins are disposed diametrically opposite each other and have pivotally mounted thereon the casing parts 9 and 10 50 of my governor, which are each preferably formed in the shape of a semi-sphere. Suitable bearings for the casing parts 9 and 10

are provided by means of the integral lugs 28 and 29 respectively. Each of the said casing parts 9 and 10 has a portion of the edge thereof, below the pivot pins 7 and 8 60 cut away, (as shown by the dotted lines in Fig. 1,) so as to allow a limited movement of these casing parts about the said pivot pins.

Disposed at right angles to the pivot pins 65 7 and 8, are ears 11 and 12 which are preferably integral with the said central shaft 5. These ears are provided with slots 13 and pivotally mounted in said slots are segmental gears 14 and 15, which are rotatably 70 mounted on pivot pins 30 and 31 respectively. These ears are also provided with apertures 30^a and 31^a, into which the pivot pins 30 and 31, respectively, may be placed so as to accommodate segmental gears, (such 75 for instance, as the gears shown in Fig. 4), giving a different multiplying ratio for the governor. The segmental gears 14 and 15 are provided with outwardly extending arms 16 and 17 respectively. These arms 80 are disposed in apertures provided in the sides of the casing parts 9 and 10, in which are preferably fitted hardened steel bushings 18 and 19 respectively. The edges of the arms 16 and 17 are preferably of spherical conformation so that they, not only fit the aperture in each bushing 18 and 19 but also have a suitable bearing contact therewith at any angle which they may assume 85 when the governor is in operation. 90

The upper end of the central shaft 5 is provided with a concentric aperture 20 which extends down into said shaft and passes by the slots 13. In this aperture is slidably disposed a spindle 21, which is provided on opposite sides with gear racks arranged to mesh with the segmental gears 14 and 15. This spindle extends up through the casing parts 9 and 10 and has its motion communicated to the valves or devices which control the flow of motive fluid to the engine or apparatus being governed, in any of the ways well known in the art. 95

22 and 23 are weights which are disposed above the pivot pins 7 and 8 and which are 100 preferably made integral with the casing parts 9 and 10, respectively. Disposed in the casing parts 9 and 10, below the pivot pins 7 and 8, are screw-threaded studs 24 and 25, respectively, each of which carries 110 one end of the compression spring 26. This spring passes through an aperture 27 in the

central shaft 5 and serves to keep the casing parts normally in the position shown in Fig. 1. The studs 24 and 25 are slotted and the compression of the spring 26 may be altered when it is desired to change the speed of revolution at which the device will govern.

In the modified form of my invention shown in Fig. 3 32 is the central shaft, which pivotally carries the casing parts 33 and 34 in a manner similar to the form shown in Fig. 1 and hereinbefore described. 35 and 36 are the segmental gears which are pivotally mounted on the pivot pins 37 and 38 respectively. Additional apertures 37^a and 38^a are also provided to permit gears, (such, for instance, as the gears shown in Fig. 4), giving a different multiplying ratio to be placed in the governor. 20 These segmental gears are provided with outwardly extending arms 39 and 40 which are disposed in the bushings 41 and 42 respectively. Arranged centrally through the upper end of the central shaft 32 is a spindle 43 which is provided on opposite sides with gear racks, engageable with the segmental gears 35 and 36.

Near the lower side of the casing parts 33 and 34 are provided, bosses 44 and 45, preferably cylindrical and each has a central counter-sunk aperture 46. In each aperture 46 is disposed a compression spring 47. A rod 48 extends through an aperture 49 provided in the central shaft 32 and through each spring 47 and has at each of its outer ends a washer 50 and a nut 57 which are arranged to bear against the outer ends of the said springs and by which the sensitivity of the governor or the speed at which it will operate may be adjusted and regulated.

The bosses 44 and 45 form the weights of the governor and may be made as heavy as required. In this form of governor, the portion of the joint between the casing parts which is below the center or pivotal points, is normally closed and that portion of the said joint which is above the center is cut away somewhat so as to allow of an upward movement of the said casing parts, 50 when the governor is in operation.

Having thus described my invention, I will now describe its operation: When the central shaft 5 of the form of my invention shown in Figs. 1 and 2, is revolved, the 55 weights 22 and 23, because of centrifugal force, tend to separate and as they do so, the casing parts 9 and 10 are revolved about the pivot pins 7 and 8. As the said casing parts revolve, the short outwardly extending arms 16 and 17 are revolved therewith and as these arms are moved downwardly, the segmental gears 14 and 15 to which the said arms are secured, are caused to revolve in an upward direction.

60 65 When the segmental gears are moved in

either direction the spindle 21 is given a reciprocating movement, in a direction corresponding to the direction of rotation of the said segmental gears.

It will be seen that the length of the arms 16 and 17 are short as compared to the pitch radii of the segmental gears 14 and 15, thus producing a multiplying effect, i. e. a slight movement of the weights causes a multiplied movement of the spindle, thereby providing a very compact and sensitive governing device.

Should the motion given to the spindle be greater than desired, the multiplying ratio of the governor may be easily changed by removing the gears 14 and 15 or 35 and 36 (Figs. 1 and 3, respectively) and substituting therefor a pair of segmental gears, each having a shorter pitch radius and a longer arm extending from the gear than the gears shown in Figs. 1 and 3, as for instance, the gears 52 and 53 shown in Fig. 4.

The operation of the modified form shown in Fig. 3 is similar to that just described, only when the central shaft thereof is revolved, the casing parts 33 and 34 will be revolved in an upwardly direction and will draw the spindle 43 downwardly, while in the form shown in Fig. 1 the casing parts 9 and 10 revolve in a downwardly direction and move the spindle 21 upwardly.

Obviously any other connecting means than teeth between the outwardly extending arms and the spindles may be employed to produce the same results as produced by the means shown. Likewise gears having pivotal points, giving a different ratio between the pitch circle of the gear and the arm may be used in place of the one shown in Figs. 1, 2 and 3, so as to produce a change in leverage and thereby alter the multiplying effect of the leverage action on the spindle of the governor.

Other modifications than those named may be made without departing from the spirit of my invention, and I do not wish to be limited to the exact construction therein shown and described.

Having thus described my invention, what I claim is:

1. A governor comprising a shaft, a two part casing centrally pivoted on said shaft, weights arranged on the periphery of said casing parts, a spindle longitudinally movable within said casing and said shaft, levers connecting said spindle with said casing parts and means for pivotally mounting different levers having different leverages at different points between said spindle and the outside walls of said casing parts, whereby the multiplying effect of the leverage action on said spindle may be altered as desired.
2. A governor comprising a shaft, a two part casing centrally pivoted on said shaft, weights arranged on the periphery of said casing parts, a spindle longitudinally movable within said casing and said shaft, levers connecting said spindle with said casing parts and means for pivotally mounting different levers having different leverages at different points between said spindle and the outside walls of said casing parts, whereby the multiplying effect of the leverage action on said spindle may be altered as desired.

2. A governor comprising a shaft, a two part casing centrally pivoted on said shaft, weights arranged on the periphery of said casing parts, a spindle longitudinally movable within said casing and said shaft, levers connecting said spindle with said casing parts and means for pivotally mounting different levers having different leverages at different points between said spindle and the outside walls of said casing parts, whereby the multiplying effect of the leverage action on said spindle may be altered as desired.

part casing centrally pivoted on said shaft, weights arranged on the periphery of said casing parts, a spindle longitudinally movable within said casing and said shaft, adjustably arranged spring means connecting the parts of said casing, levers connecting said spindle with said casing parts, and means for pivotally mounting different levers having different leverages at different points between said spindle and the outside walls of said casing parts whereby the multiplying effect of the leverage action on said spindle may be altered as desired.

3. In a governor of the combination of a shaft, a two part casing centrally pivoted on said shaft, weights arranged on the periphery of said casing parts, a spindle provided with racks longitudinally movable within said casing and said shaft, adjustable arranged spring means connecting the parts of said casing, and lever means connecting said spindle with said casing parts comprising, segmental gears arranged to mesh with the racks on said spindle and pivotally mounted on said shaft within the periphery of said casing parts, and outwardly extending arms secured to said segmental gears and engageable with said casing parts.

4. In a governor of the combination of a shaft, a two part casing centrally pivoted on said shaft, weights arranged on the periphery of said casing parts, a spindle provided with racks longitudinally movable within said casing and said shaft, adjustably arranged spring means connecting the parts of said casing, and lever means connecting said spindle with said casing parts comprising, segmental gears arranged to mesh with the racks on said spindle and pivotally mounted on said shaft at a greater distance from said spindle than from the periphery of said casing parts, and outwardly extending arms secured to said segmental gears and engageable with said casing, whereby the longitudinal movement of said spindle is multiplied by the movement of said weights.

5. In a governor of the combination of a shaft, oppositely arranged pivot pins carried by said shaft, a two part casing centrally pivoted on said pivot pins, weights arranged on the periphery of said casing parts, a spindle provided with racks and longitudinally movable within said casing and said shaft, ears on said shaft each provided with a slot, segmental gears pivotally carried by said ears in said slots and arranged to mesh with the racks on said spindle, and outwardly extending arms secured to said segmental gears, engageable with said casing parts, said segmental gears being pivoted at a greater distance from said spindle than from the periphery of said casing, whereby the longitudinal movement of said spindle is multiplied by the movement of said weights.

6. In a governor of the combination of a shaft, oppositely arranged pivot pins carried by said shaft, a two part casing centrally pivoted on said pivot pins, weights arranged on the periphery of said casing parts, above said pivot pins, adjustable spring means connecting said casing parts and disposed below said pivot pins, a spindle provided with racks and longitudinally movable within said casing and said shaft, ears on said shaft each provided with a slot, segmental gears pivotally carried by said ears in said slots and arranged to mesh with the racks on said spindle, and outwardly extending arms secured to said segmental gears and engageable with said casing parts, said segmental gears being pivoted at a greater distance from said spindle than from the periphery of said casing, whereby the longitudinal movement of said spindle is multiplied by the movement of the weights.

In testimony whereof, I have hereunto set my hand in the presence of two witnesses.

HERMAN A. WEIDENBACH.
